UNITED STATES PATENT OFFICE.

ROBERT BLANK, OF COLUMBUS, OHIO, ASSIGNOR TO SOLAR-STURGES MFG. CO., OF CHICAGO, ILLINOIS, A CORPORATION OF ILLINOIS.

FIREPROOF WASTE CAN.

Application filed July 14, 1921. Serial No. 484,723.

To all whom it may concern:

Be it known that I, ROBERT BLANK, a citizen of the United States of America, residing at Columbus, in the county of Franklin and State of Ohio, have invented certain new and useful Improvements in Fireproof Waste Cans, of which the following is a specification.

My present invention relates to receptacles, 10 and particularly to the arrangement of a closure or closures and a mechanism for automatically actuating the same. The invention may be used in connection with various receptacles where it is desired to prevent the 15 escape of odors, to exclude vermin, or to prevent communication of fire.

I show the invention as embodied in a waste-collecting can which includes a body and a removable cover. The cover is provided with diametrically opposed door openings and with inward swinging doors for closing such openings. The door actuating mechanism is housed within the cover between the doors and comprises a yielding 25 linkage connected with the doors and operating to urge both doors closed at all times, while permitting either door or both to be pushed open against moderate resistance. In this preferred form, the closing mechanism 30 is so contrived as to exert a closing tendency on the doors which is greatest when both doors are closed.

In the accompanying drawing which illustrates my invention,

35 Figure 1 is a side view of the can complete,

Figure 2 is an enlarged vertical section through the upper portion of the can including its cover,

40 Figure 3 is a bottom plan view of the cover removed, and

Figure 4 is a view similar to Figure 2, showing one of the doors in open position.

45 Referring now to these figures my invention is utilized in connection with a vertical cylindrical can body 10 having a closed base and an upper open end provided with a reinforced surrounding edge 11, telescopingly engaged by the lower offset flange 12 of the 50 open end of a substantially semi-globular cover 13.

The cover 13 has at diametrically opposite points openings 14 through which material may be introduced within the can while the 55 cover is in closed position, these openings be-

ing normally closed by a pair of inward swinging doors 15 within the cover, hinged at their upper edges at 16 to the inner surface of the cover, and having lower lips 17 adapted to engage the edges of the cover 60 along the lower portions of its openings 14.

Each door 15 has inner brackets 18 to which are pivoted the outer ends of inwardly projecting and upwardly curving links 19, whose inner ends are pivotally connected to 65 one another by a cross rod 20, the inner ends of certain of these links 19 having enlargements 21 which form weights and thus operate by gravity to hold the doors 15 in their outer positions closing the cover openings 70 14.

The links 19 with their pivotal connections to the doors and to each other form a toggle in which the links 19 serve as strut links. The parts are so proportioned and arranged, 75 that when both doors are closed the toggle does not completely straighten and in all positions which the doors may assume the weight of the enlargements 21 urges both doors toward their closed positions. Thus 80 either door may be pushed open regardless of the position of the other door and, when released, will be automatically closed.

It should be observed that the pivots at the 85 ends of the links 19 approach alignment as the doors close. Consequently, the closing thrust exerted on the doors by the weight of the enlargements 21 is greatest when both doors are closed. This is a valuable characteristic for it insures maintenance of the 90 doors in closed position, while allowing the doors to open with increasing ease as the opening movement progresses. This characteristic has special utility in structures such as that shown in the drawing, in which the door is so positioned when closed as to have an opening tendency due to its own weight.

Thus it is obvious that while effectively operating to maintain both doors in closed position, the connections between the doors 100 are such that they may readily yield to permit the opening of either door for the purpose of introducing material within the can, the door or doors so opened automatically closing when released so that the can will be 105 maintained in fireproof relation in so far as the communication of fire either to or from its contents is concerned.

I claim:

1. A fireproof waste can including a body,

- a removable cover for the body having oppositely disposed door openings, doors hinged to and swingable within the cover and seatable against the inner face of the cover around said openings, and vertically yieldable connections between the doors, free of contact with the cover and acting by gravity to normally hold the doors in their outer closed positions.
- 10 2. A fireproof waste can including a body, a removable cover having oppositely disposed side door openings, doors swingable within the cover to seat against its inner face around said openings, and gravity controlled pivotal connections vertically yieldable between the doors and free of contact with the cover, for holding the doors by gravity in outer closed positions.
- 15 3. The combination of a receptacle having an opening; an inward opening door hinged to said receptacle and serving to close said opening; and a gravitating toggle linkage mounted within said receptacle, connected with said door, and serving to urge said door closed with a thrust which increases as the door approaches closed position.
- 20 4. The combination of a receptacle having a pair of openings; inward opening doors hinged to said receptacle and serving to close said openings; and a gravitating toggle linkage mounted within said receptacle, connected with said doors and urging each door toward closed position independently of the position of the other door.
- 25 5. The combination of a receptacle having a pair of openings; inward opening doors hinged to said receptacle and serving to close said openings, said doors having an opening tendency due to their own weight when closed; and a gravitating toggle linkage mounted within said receptacle, connected with said doors and serving to urge each door closed regardless of the position of the other door, said linkage being constructed and arranged to exert its greatest thrust against said doors when both doors are closed.
- 30 6. The combination of a receptacle having opposed openings; inward opening doors hinged to said receptacle and serving to close said openings; a pair of links hinged to said doors and to each other; and means for urging said links toward alinement with each other, whereby a closing tendency is exerted upon the doors.
- 35 7. The combination of a receptacle having a plurality of openings; a plurality of inward opening hinged doors arranged to close said openings; a weight; and a plurality of links connected with said weight and each link connected with a corresponding door, the weight and links being so arranged that the weight constantly exerts a closing tendency on all the doors, in all positions thereof.
- 40 8. The combination of a receptacle having a pair of openings, inward opening doors hinged at their upper ends to said receptacle and serving to close said openings, said doors having an opening tendency due to their own weight when closed, and links having outer ends pivotally connected to the lower ends of said doors and also having weighted inner ends pivotally connected to each other, the lengths of said links being sufficient to prevent the inner ends thereof from passing downwardly below the center line of the pivots for their outer ends.
- 45 In testimony whereof I have affixed my signature.

ROBERT BLANK.
